UNITED STATES PATENT OFFICE.

EDWIN WAGNER, OF MOLALLA, OREGON.

EQUALIZER.

1,239,988.

Specification of Letters Patent. Patented Sept. 11, 1917.

Application filed September 27, 1916. Serial No. 122,502.

To all whom it may concern:

Be it known that I, EDWIN WAGNER, a citizen of the United States, residing at Molalla, in the county of Clackamas and State of Oregon, have invented certain useful Improvements in Equalizers, of which the following is a specification, reference being had therein to the accompanying drawing.

10 This invention relates to a whiffletree adjuster and more particularly to the class of draft equalizers.

The primary object of the invention is the provision of a device of this character wherein the whiffletree can be readily and conveniently adjusted with despatch so as to vary the draft of the load to either side of the neutral line of draft, thereby enabling the strain or pull to be equalized where 20 the draft animals of unequal strength are hitched to the load.

Another object of the invention is the provision of a device of this character wherein the construction thereof is novel in form so 25 that the whiffletree can be locked in its adjusted position without possibility of the accidental freeing thereof and when in locked position will serve to equalize the strain or pull of the load.

30 A further object of the invention is the provision of a device of this character which is extremely simple in construction and thoroughly reliable and efficient in its operation, strong, durable and inexpensive in 35 manufacturing and installation.

Other objects will be in part obvious and in part hereinafter pointed out.

The invention accordingly consists in the features of construction, combination of elements and arrangement of parts which will be exemplified in the construction herein-after set forth and the scope of the application of which will be indicated in the claims hereunto appended.

45 In the accompanying drawings:

Figure 1 is a perspective view of the whiffletree showing the device constructed in accordance with the invention applied thereto.

Fig. 2 is a fragmentary horizontally longitudinal sectional view thereof.

Fig. 3 is a sectional view of Fig. 1.

Fig. 4 is a vertical transverse sectional view of the whiffletree showing the device released from its rack-bar.

55 Similar reference characters indicate cor-

responding parts throughout the several views in the drawing.

Referring to the drawing in detail, A designates generally a whiffletree which is of any well known construction and has applied thereto the device hereinafter fully described.

The device comprises a flat bar 5 formed medially thereof throughout its longitudinal extent with a series of inset rack-teeth 6 while at opposite ends of the said bar are formed perforated ears 7 through which are passed suitable fasteners for securing the bar 5 to the front edge of the whiffletree A, intermediate the ends thereof. Of course it is to be understood that this bar 5 can be formed integral with the whiffletree A or can be a separate part therefrom and fastened thereto in any suitable manner as the occasion may require.

75 Slidable upon the front or outer face of the bar 5 is an adjustable hanger block 8 of the conformation as shown although it may be of any other desirable shape and this block is formed at opposite ends with guide-ears 9 which engage in guide grooves 10 formed in the opposite longer edges of the rack-bar 5 and in this manner the said block 8 is slidably connected to the bar 5 for free movement thereon, whereby the said block 80 can be positioned at any point between the ends of the bar, for a purpose presently described.

75 Formed in the block 8, spaced from the ends thereof are suitable guideways in which 90 work locking members 11 which are adapted to engage with the rack-teeth 6 on the bar 5 for holding the block 8 in its adjusted position upon the bar. Suitably mounted upon the block 8 and working against the locking 95 members 11 are leaf springs 12 which positively hold the said locking members in engagement with the rack-teeth 6 on the bar 5 until the said members 11 are released in a manner presently described.

100 Swingly connected to and mounted upon the block 8 is a cap 13 which is of a shape corresponding to the outer medial portion of the block and is supported for swinging movement upon pivots 13' arranged at 105 one end of the cap, the cap being cut away at 14 to serve as a clearance in the swinging movement thereof.

110 Loosely connected to the locking members 11 and also loosely connected to the cap 13

are pull links 15 which serve to move the locking members 11 out of engagement with the rack-teeth 6 when the cap is swung from its normal position in contact with the outer 5 face of the block 8 to substantially horizontal position and when the cap is in this position it will hold the members 11 released from the rack-teeth 6 on the bar 5 so that said block can freely move thereon to 10 any desired adjusted position.

The cap 13 is formed with the finger hold 16 so that the cap can be readily pulled outwardly for releasing the locking members 11 from engagement with the teeth 6 on the bar 15 5 to permit free adjustment of the block 8 thereon.

The links 15 are connected with the cap 13 so that when the latter is in horizontal position the locking members 11 will be sustained in released position against the 20 resistance of the springs 12 until said cap is moved to normal position against the block 8.

Formed in the block 8 centrally thereof is a hole 17 which receives the bolt 18 carried by the loop or yoke 10 which extends back over the rear edge of the doubletree A and is adapted to be secured to a wagon or other vehicle and in this manner the said double tree is hung thereon.

30 When it is desired to adjust the double tree so as to equalize the strain upon the draft animals the cap 13 is taken hold of and the same pulled outwardly away from the block 8. It will be noticed that the 35 springs 12 serve not only to hold the locking members 11 in engagement with the ratchet teeth but also assist in holding the pins 13' against the back edges of the recesses 17' which are found in the block 8. Therefore 40 by pulling the cap outwardly the locking members are disengaged from the ratchet teeth 6 on the bar 5, the pins 13' sliding in the recesses 17' to allow this. At the same time the cap is thus operated upon, the block 45 8 can be freely moved upon the bar either to the right or to the left until the bolt 18 is brought to the desired position. By remov-

ing pressure from the cap the locking member 11 will again engage the ratchet teeth and thus lock the block against further 50 movement, and the parts will be in normal position again.

From the foregoing, it is thought that the construction and manner of operation of the device will be clearly understood and 55 therefore a more extended explanation has been omitted.

What is claimed is:

1. In a device of the class described, in combination, a whiffle tree, an elongated rack bar secured thereagainst, a slidable block guided upon said rack bar and having its front wall slidable upon the teeth of said rack bar, a series of locking members slidably mounted in said slidable block 60 and having points adapted to engage said rack teeth, a leaf spring secured at one end to each end of said block and secured also to said locking members so as to hold the latter against the rack teeth, and means secured to said locking members adapted to disengage the same from said rack teeth. 65

2. In a device of the class described, in combination, a whiffle tree, a rack bar secured against one edge thereof, a slidable block 70 slidably guided against said rack bar, a pair of opposed locking members adapted to engage the teeth of said rack bar, leaf springs secured to said block and also to the rear ends of said locking members, a cap adapted to extend opposite said blocks so as to straddle the sides thereof, said block being formed with side recesses, pins carried by said cap and adapted to slide in said recesses, link rods pivotally secured to said 75 cap and to the rear ends of said locking members, said springs normally holding said pins against the back walls of said recesses and said locking members against said rack teeth, and a handle secured to said cap by 80 which it may be retracted from said block to disengage said locking members. 85

In testimony whereof I affix my signature.
EDWIN WAGNER.
